GAME

Charles E. Wood, Highland, N. Y.

Application May 15, 1935, Serial No. 21,637

1 Claim. (Cl. 273—89)

The invention relates to a game device and more especially to a game board for the playing of the national game of American baseball.

The primary object of the invention is the provision of a board of this character, wherein the playing surface thereof is constructed to imitate an outdoor playing field for the playing of the national game of American baseball and wherein the plays of this game can be carried forth or executed as truly imitative of those plays made in the outdoor playing by league teams and under standard rules for so doing, thus lending attractiveness and requiring skill in the playing thereof.

Another object of the invention is the provision of a game board of this character, wherein the diamond is associated with an infield and an outfield, these being indicated on the playing surface of the board, movable balls or spheres are projected in a novel manner for the execution of plays imitative of the national game of American baseball, thus the players can be grouped in offensive and defensive teams for the scoring of the plays made and the winning team can be awarded a championship prize.

A further object of the invention is the provision of a game board of this character, which is simple in construction, novel in its makeup, strong, durable, readily portable, and inexpensive to manufacture.

With these and other objects in view, the invention consists in the features of construction, combination and arrangement of parts as will be hereinafter more fully described, illustrated in the accompanying drawings, which disclose the preferred embodiment of the invention and pointed out in the claim hereunto appended.

In the accompanying drawings:

Figure 1 is a plan view of the game board constructed in accordance with the invention showing the feed medium for projecting a ball or sphere onto the playing surface of the board in position and also a batting medium usable for an execution of a play in operative position.

Figure 2 is a fragmentary sectional view on the line 2—2 of Figure 1 looking in the direction of the arrows.

Figure 3 is a sectional view taken on the line 3—3 of Figure 1 looking in the direction of the arrows.

Figure 4 is a fragmentary sectional view on the line 4—4 of Figure 1 looking in the direction of the arrows.

Figure 5 is a mutilated sectional view taken on

the line 5—5 of Figure 1 looking in the direction of the arrows.

Figure 6 is an end elevation of the board partly broken away.

Figure 7 is a perspective view of the batting medium.

Figure 8 is a fragmentary vertical longitudinal sectional view through the projecting medium.

Figure 9 is a fragmentary sectional view on the line 9—9 of Figure 1 looking in the direction of the arrows.

Similar reference characters indicate corresponding parts throughout the several views in the drawings.

Referring to the drawings in detail, the game board comprises a flat table-like playing bed 10 which is secured in a frame that comprises side and end walls 11 and 12, respectively, they being uniform in height with relation to each other. Provided at opposite ends of the board and parallel with the end walls 12 and next thereto are the troughs 13 and 14, respectively, which meet the side walls 11. These troughs 13 and 14 are sunken with relation to the top playing face of the playing bed 10 and have their bottoms 15 flush with the lowermost edges of the side and end walls 11 and 12 of the frame.

Upon the playing or upper surface of the bed 10 at the proper locality is painted or stamped a diamond 16 imitative of a baseball diamond, the said diamond being stamped, painted or otherwise outlined upon the upper surface of said bed 10 and included with its representation is a home plate 17, first base 18, second base 19 and third base 20, respectively. At the representation of first, second and third bases there are gullies 21 which constitute in and out leads to and from the same while at each base is a ball seat 22 for accommodating the stationing of a ball 23 at these respective places. The bases are identified by the words "First base", "Second base" and "Third base" as printed or otherwise impressed upon the playing surface of the bed 10.

The area 24 within the diamond 16 constitutes the infield while the area 25 outside of this diamond constitutes the outfield, there being in the infield a pitcher's box or stand, this being effected by a ball seat or hole 26 and identified by the words "Strike" and "Ball" supplemented by the digits "2" to the right and left sides of the seat 26, these words being printed or otherwise impressed on the playing face of the bed 10.

In the outfield 25 there is provided ball seats or holes 27, these being specially located and are identified by the words "Error", "Base",

"Double Out" and "Home Run." Those seats or holes 27 identified by the word "Base" are supplemented by the digits "1", "2" and "3" so that when a ball is seated in this series of holes 5 by the supplemental digits it can be determined the count whether it be a one-base hit, two-base hit or a three-base hit, while the seats or holes identified by the words "Home Run" enable the determining of a hit as a home run on the deposit 10 or seating of a ball in such hole or holes. The other holes or seats 27 are indicative of the character of play as identified by the words in association therewith.

Beyond the home plate 17 and located as is conventional for a catcher in the playing of the baseball game is a clapper 28 which is hinged at 29 to the end wall 12 next thereto and this clapper is weighted at 30 to hold the same normally inclined in the direction of the home plate and 20 on the striking thereof true by the ball it will be tilted for the sounding of a gong or bell 31 carried by said end wall 12 and thus signalling a strike on a batsman. The ball when striking the clapper 28 true when the latter tilts will become 25 deposited in the trough 13 therebeneath while the weight 30 after dismissal of the ball returns the clapper to normal position as is shown in Figures 1, 4 and 5 of the drawings. The object of this clapper also is to prevent swift balls from 30 bouncing back and out.

Disposed at opposite sides of the clapper 28 are vertically arranged inwardly divergent side guards 32 so that a ball projected therebetween will be deflected in the direction of the clapper.

35 Next to the opposite sides 11 of the board and close to the trough 13 beneath the clapper are the inwardly curved bumpers and ball retarding members 44 functioning to direct a ball or balls when projected on the playing surface or face of the bed 10 when irregularly struck or thrown into 40 pockets 33 for the trapping of the ball irregularly batted or projected and the same being indicative of a ball in contradistinction to a strike as accounted against a batsman and pitcher. 45 From these pockets 33 the balls are readily removed.

Located adjacent to the home plate side of the diamond or frame 16 are ball pockets or holes 34, these being identified by the words 50 "Take Base" so that when a ball is seated therein it is indicative that a batsman has been hit by a projected ball or has a count in his favor of four pitched balls entitling him to take first base in the playing field.

55 The other trough 14 has the ball rack 35 for accommodating the spent balls projected onto the playing field of the game board, the end wall 12 next to this rack 35 being cut away at 36 for convenient access to the rack whereby the balls held therein can be easily removed.

At the outermost end of the outfield 25 is a partition 37 which rises vertically in parallel relation to the end wall 12 next thereto and this partition is provided with gateways 38 which 60 permit the spent balls to pass through the partition to be deposited within the rack. A ball or balls passing through the gateway 38 in the partition 37 gives a count of an out.

Arranged upon the partition 37 at its top edge 70 is a prop 39 for an adjustable conveyer 40 which is of substantially V-shape in cross section and which is adapted to be passed a ball or balls 23 for the projecting thereof onto the playing face of the bed 10 and this conveyer 40 is a substitute 75 for a pitcher for the ball. The conveyer at the

outermost end has arranged therein a sponge 41 with which to moisten the fingers to facilitate the pitching of curves and this conveyer is manually manipulated for sliding movement through the prop 39 or tilting movement to control the 5 projecting of the ball to be played on the playing field of the bed 10 of the board.

The batsman's bat or striking medium comprises a pole or handle 42 having a striking head 43 at one end and such implement is positioned 10 between the home plate 17 and the clapper 28 at the playing surface of the bed 10 in the position as shown in Figure 1 of the drawings and on the sending of a ball 23 from the conveyer 40 the holder of such batting medium by skill or 15 otherwise can strike the ball for the sending of the same to be imitative of the batting thereof onto the playing field for scoring purposes.

It should be obvious that by skilled manipulation of the conveyor 40 the ball 23 can be sent 20 onto the playing field of the board imitative of a slow and fast speed ball, curved and inner, outer and drop shots as effected by a human being serving as a pitcher in the game of baseball. The slanting of the conveyor 40 regulates the speed 25 of travel of the ball onto the playing surface of the bed.

In the use of the game board and similar to the playing of the regular game of baseball the game consists of nine innings. Three outs is an 30 inning.

The team playing outfield lines up to pitch in turn while the other team which is termed the batting team lines up to bat in regular turn, or each player can pitch for an entire inning in 35 turn.

Pitching is accomplished by rolling the ball down the conveyor 40, the object being to get strikes on the batsman by getting the ball over home plate into the strike pocket or gulley. The 40 speed of the ball is controlled by the slant of the conveyor 40 and by practice a pitcher by moistening his fingers on the sponge in the conveyor and snapping the ball to right or left can accomplish tricky curves and many strike outs 45 by changing from slow to fast balls alternately.

If the batsman swings his bat or by the implement 42 attempts to strike the ball, it is considered a strike. If the batsman strikes the ball and it does not roll into a pocket it is a strike. 50 If the batsman does not strike at the pitched ball and it goes into the pocket 33 on either side of the center strike pocket it is called a ball. If the ball goes into strike pocket whether hit or not it is a strike. Four balls as counted against the 55 pitcher and in favor of the batsman allow the placing of a ball on first base which is indicative of the batsman making first base. A ball in strike pocket is a strike even though it may sometimes bounce out. When a batsman occupies 60 first base it signifies a single hit, the occupancy of second base signifies a two-base hit and the occupancy of third base signifies a third-base hit. A ball in the pocket 26 is indicative of two strikes when hit there by batter or two balls for batter 65 when placed there by poor pitching. When a ball is on first base and a short stop hit is made it is indicative of a double play, two outs. A ball in an error pocket is a one-base hit. If a ball is on first base and a ball rolls into error pocket, the ball on first base moves to second base and the error ball is placed on first base. A home run brings in all balls on the bases and scores a run for each. All balls struck and not going into the 70 pocket other than the balls on the bases remain 75

on the board only until the next batsman is up. In event of two balls going into pockets on the same hit the one that goes in first rules or scores, for example: Suppose the ball drops into home 5 run pocket first and another ball drops into third-base hit pocket later, the score would be one run and a third-base hit, whereas if a third-base hit ball went in first the score would be two runs.

10 A batsman knocking any ball through gateways 38 in the partition 37 or a batsman knocking a ball off the board is scored out. A pitched ball going into a pocket due to poor aim by the pitcher counts for the batsman. A foul ball rolled by 15 a pitcher is a ball count for a batsman. If a pitcher allows a ball to be pitched before a previously pitched ball comes to a complete stop on the board the batsman goes to first base, the reason for this being so that the batsman's attention is distracted by watching the rolling ball. 20 The batsman holds the striking medium or batting medium flat onto the board with the handle 42 facing the top when a ball is pitched. This batting medium must be at least two inches off 25 of home plate 17. The person pitching is not allowed to push or throw the ball down the conveyor 40. A disinterested person may act as 30 umpire when the game board is in use for playing the national game of American baseball.

The batsman is out when he has three strikes called on him, even though the last ball pitched might have bounced into a hole representing a hit.

Teams can be organized and games played for

championship prizes. A team to win must have a count of four consecutive games in its favor. A lost game in between the four consecutive games取消s the series whence the playing must be started over again.

Of course, the foregoing rules and regulations are merely tentative as certain rules and regulations may be compiled by the teams created or formed for the use of the board in the playing of a baseball game.

Intermediate of the opposite sides 11 of the board and upon the bottom of the trough 13 beneath the clapper is an arched member 45 for deflecting the balls right and left and in this manner avoiding a jam in the strike box of the 15 game board.

At a pair of the corners of the board are the corner guards 46.

What is claimed is:

A game board, comprising a bed which is secured in a diamond and which has laterally extending troughs at both of its ends, a prop for an adjustable ball conveyor on the bed adjacent to one of the troughs and whereby balls may be projected over the bed toward the second trough, a 25 weight influenced pivotally supported clapper swingable into said second trough when contacted by a projected ball for delivering such ball into said trough and for striking an alarm, an arched member for directing the ball to either side of the 30 trough, and outwardly diverging guards at the sides of said clapper.

CHARLES E. WOOD.
